Primary Examiner — John Windmuller(74) *Attorney, Agent, or Firm* — Fattibene and Fattibene LLC; Paul A. Fattibene(57) **CLAIM**

The ornamental design for a conduit coupling, as shown and described.

DESCRIPTION

FIG. 1 is a perspective view of a conduit coupling showing the new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right side elevation view thereof, with the left side elevation view being a mirror image.

The broken lines shown are for illustrative purposes only and form no part of the claimed design.
